Attorney

UNITED STATES PATENT OFFICE.

CARL HOFFMAN, OF ALLENTOWN, PENNSYLVANIA.

AUTOMOBILE SIGNAL.

Application filed March 31, 1923. Serial No. 629,143.

To all whom it may concern:

Be it known that I, CARL HOFFMAN, a citizen of the United States, and resident of the city of Allentown, county of Lehigh, and 5 State of Pennsylvania, have invented new and useful Improvements in Automobile Signals, of which the following is a specification.

My invention relates to annunciators, such 10 as are carried by automobiles, indicating traffic conditions and the object of my invention is to provide a simple and highly efficient signal of this class which is readily actuated through circuits controlled by 15 switches, preferably located on the steering wheel of the automobile, the signal elements being compactly arranged within a single housing which is mounted on the rear left fender of the vehicle.

20 In the drawings:

Fig. 1 is a view in side elevation of a touring car equipped with my annunciator.

Fig. 2 is an enlarged view of the signal box or frame, with one of the face plates 25 moved to show the interior arrangement.

Fig. 3 is a view in side elevation of the signal box or frame, and

Fig. 4 is a vertical sectional view thereof.

Fig. 5 is a cross sectional view on line 30 5-5 of Fig. 2.

Fig. 6 is a diagram of the controlling circuits.

The signal box is preferably supported by a hollow spindle 1 on the rear fender of 35 the vehicle and includes a rectangular frame 2 spacing front and rear transparent plates 3 and 4, respectively, upon which are printed the words "Stop", "Right" and "Left", in the order named from top to bottom. These 40 words are preferably printed in red upon a white ground, so as to produce the most effective display.

The frame 2 has horizontally disposed 45 partitions 5 separating the interior of the frame into three compartments, one for each of the noted traffic directions. The surfaces of these partitions are highly polished to aid in reflecting the light of electric lamps 6, two of which are located in each of the 50 compartments, the sockets 7 being projected through openings in the sides of the frame.

These sockets 7 are supported by channeled members 8, which are secured to the sides of the frame 2, this channeled formation 55 providing a means by which the wiring is carried to the lamp sockets.

A conduit 9 at the bottom of the frame 2 forms part of the spindle 1 and communicates with the channeled members 8.

A cap piece 10 serves to hold at the top 60 angular moldings 12 which bind the plates 3 and 4 to the frame 2, these moldings being fastened to the frame at the sides by screws 13.

For the purpose of avoiding rattling between the partitions 5 and the front and rear plates 3 and 4 and for the additional purpose of making the compartments light tight, I place a strip of rubber 14 between such partitions 5 and the plates 3 and 4. 65

The operation of my improved annunciator will be readily apparent from the diagrammatic showing in Fig. 6, wherein the source of electric energy is indicated at 20, leads to the "stop" compartment being 70 shown at 21, with a control button 22 on the steering wheel; leads to the "right" compartment at 23 with control button 24; and leads to the "left" compartment at 25, with control button 26. 75

I claim as my invention:

1. An annunciator for motor vehicles including a frame with openings in the front and rear, horizontally disposed spaced apart partitions forming compartments in said frame, such partitions being provided with reflecting surfaces, transparent plates adapted to close the openings of said frame and upon which traffic signals are indicated, a channeled member attached to each side of 85 said frame, lamp sockets carried by said members and respectively disposed in the compartments formed by said partitions, a conduit communicating with said channeled members, a spindle forming a continuation 90 of said conduit for supporting said frame on a part of the motor vehicle, said channeled members, conduit, and spindle being adapted to carry wires for supplying current to 95 said lamps.

2. An annunciator for motor vehicles including a frame with openings in the front and rear, horizontally disposed spaced apart partitions forming compartments in said frame, such partitions being provided with reflecting surfaces, transparent plates adapted to close the openings of said frame and upon which traffic signals are indicated, moldings for securing said plates in position, means for preventing rattling between said 105 plates and said horizontally disposed partitions, a cap piece carried by said frame and 110

adapted to impart and engage said moldings to hold them in position, a channeled member attached to each side of said frame, lamp sockets carried by said members and respectively disposed in the compartments formed by said partitions, a conduit communicating with said channeled member, a spindle forming a continuation of said conduit for

supporting said frame on a part of the motor vehicle, said channeled members, conduit, and spindle being adapted to carry wires for supplying current to said lamps.

In testimony whereof I have signed this specification.

CARL HOFFMAN.
